ABSTRACT

A system that manages at least one consumable material used by at least one device includes a memory storing instructions, and a processor executing the instructions causing the system to manage information regarding the consumable material for at least one container, acquire consumed amounts of the consumable material or remaining amounts of the consumable material from the at least one device using the consumable material in the respective container, and transmit information regarding a request to deliver a new container of the consumable material to a delivery service that delivers the new container of the consumable material used by the at least one device on the basis of a total amount of consumption obtained by summing the consumed amounts of the consumable material or the remaining amounts of the consumable material.

**SYSTEM, NETWORK DEVICE, SYSTEM
CONTROL METHOD, AND RECORDING
MEDIUM**

FIELD

The present disclosure relates to a system that manages a consumable material, a network device, a system control method, and a recording medium.

DESCRIPTION OF THE RELATED ART

In the related art, there is a system that transmits the amount of consumed ink, which is a consumable material, to a server, manages the remaining amount of ink, and automatically delivers a replacement ink cartridge if the remaining amount of ink reaches a predetermined level. Japanese Patent Laid-Open No. 2016-194771 discloses a server device that acquires the remaining amount of ink and a printer ID from a printer and provides an instruction to deliver a cartridge to a user of the printer corresponding to the printer ID to an external device in a case where the remaining amount of ink is equal to or less than a threshold value. On the other hand, a printer including a refillable liquid tank where ink of a liquid bottle can be refilled has appeared in recent years. In such a printer, there is a likelihood that the ink may remain in the ink bottle when the remaining amount of ink with which the printer is filled is low. Japanese Patent Laid-Open No. 2021-30459 discloses a print device that estimates a timing at which consumption of ink with which an ink bottle is filled will be completed on the basis of the amount of ink consumed per predetermined period of time and provides a request to deliver an ink bottle before consumption of the ink is completed.

Although the print device according to Japanese Patent Laid-Open No. 2021-30459 provides the request to deliver an ink bottle on the basis of the amount of consumed ink used by the device itself (one printer), the ink bottle can be used by a plurality of printers together, in general. The system according to Japanese Patent Laid-Open No. 2021-30459 cannot calculate a timing at which consumption of the ink in the ink bottle will be completed in the case where a plurality of printers calculate the amount of consumed ink, and the system cannot deliver the ink bottle before consumption of the ink bottle is completed.

SUMMARY

The present disclosure provides a system that places an order for a consumable material at an appropriate timing.

According to an aspect of the present disclosure, a system that manages at least one consumable material used by at least one device includes a memory storing instructions, and a processor executing the instructions causing the system to manage information regarding the consumable material for at least one container, acquire consumed amounts of the consumable material or remaining amounts of the consumable material from the at least one device using the consumable material in the respective container, and transmit information regarding a request to deliver a new container of the consumable material to a delivery service that delivers the new container of the consumable material used by the at least one device on the basis of a total amount of consumption obtained by summing the consumed amounts of the consumable material or the remaining amounts of the consumable material.

Further features of the present disclosure will become apparent from the following description of exemplary embodiments with reference to the attached drawings.

5 BRIEF DESCRIPTION OF THE DRAWINGS

FIG. 1 is a diagram illustrating a hardware configuration of a printer.

FIG. 2 is a diagram illustrating an appearance of the 10 printer.

FIGS. 3A and 3B are diagrams for explaining an ink tank and ink.

FIG. 4 is a diagram illustrating a configuration of a system according to a first embodiment.

15 FIG. 5 is a diagram for explaining a mechanism of ink supply.

FIG. 6 is a diagram illustrating an appearance of an ink bottle.

20 FIG. 7 is a diagram for explaining an ink bottle record managed by the printer.

FIG. 8 is a diagram illustrating a hardware configuration of a mobile terminal.

FIG. 9 is a diagram illustrating a software configuration of the mobile terminal.

25 FIG. 10 is a diagram for explaining a printer record managed by the mobile terminal.

FIG. 11 is a diagram for explaining an ink bottle record managed by the mobile terminal.

FIG. 12 is a sequence diagram illustrating processing of 30 registering a printer.

FIGS. 13A to 13D are diagrams illustrating examples of display on the mobile terminal.

FIG. 14 is a sequence diagram illustrating processing of 35 registering an ink bottle.

FIG. 15 is a sequence diagram illustrating processing of determining a request to deliver ink.

FIG. 16 is a sequence diagram illustrating processing of 40 determining a request to deliver ink.

FIGS. 17A and 17B are diagrams illustrating examples of 45 a screen for displaying a result of determining delivery of an ink bottle.

FIG. 18 is a diagram illustrating a configuration of a system according to a second embodiment.

45 DESCRIPTION OF THE EMBODIMENTS

First Embodiment

FIG. 1 is a diagram illustrating a hardware configuration of a printer 100. The printer 100 according to an embodiment is an image forming device including an ink tank 110, into which ink from a liquid bottle that is a consumable material can be refilled, and adapted to perform printing by ejecting the ink supplied from the ink tank 110. Although a 55 case where the printer 100 is a digital multifunction peripheral (MFP) having a print function and a scan function will be described as an example in the present embodiment, the printer 100 may be any printer as long as it has a function of forming an image by ejecting ink. For example, the printer 100 may be a single-function printer, a copy machine, a facsimile, or the like.

The printer 100 includes a CPU 101, a ROM 102, a RAM 103, and an EEPROM 104. The central processing unit (CPU) 101 controls each part in the printer 100. The read only memory (ROM) 102 stores various program codes. The random access memory (RAM) 103 temporarily stores image data and the like at the time of execution of various

services and performs buffering. Also, the RAM 103 functions as a work area or the like of the CPU 101. The CPU 101 comprehensively controls each part connected to a system bus 111 and controls the entire printer 100 by executing a program stored in the ROM 102.

The electrically erasable programmable read-only memory (EEPROM) 104 is a non-volatile memory and stores various kinds of data. The data stored in the EEPROM 104 is, for example, shipping destination information of the printer 100, an ink bottle record, setting of a language displayed on a display portion 106, and the like. Details of the ink bottle record will be described later by using FIG. 7.

The printer 100 further includes a communication portion 105, the display portion 106, and an operation portion 107. The communication portion 105 is connected to an external device via a USB or a network and performs communication with the external device. The RAM 103 also temporarily stores image data and the like that the communication portion 105 receives from the external device. The display portion 106 includes, for example, a liquid crystal display and displays letters, figures, indicators, and the like. The display portion 106 is not limited to the liquid crystal display and can also be configured by using an LED or another display machine. Examples of information displayed on the display portion 106 include setting information of the printer 100, information regarding ink accommodated in each ink tank, and the like. The information regarding ink includes information regarding the remaining amount of the ink accommodated in the ink tank, information regarding an instruction to refill ink, and the like. The display on the display portion 106 is controlled by the CPU 101. The operation portion 107 includes a switch, a hard key, and the like for allowing a user to perform various input operations and receives input operations from the user. Additionally, it is also possible to adopt a mode in which the display portion 106 performs a function as the operation portion 107 for performing input operations like a touch panel. It is possible to configure a GUI that allows the user to perform operations as if the user were able to operate the screen displayed on the touch panel directly by associating input coordinates with display coordinates on the touch panel.

Also, the printer 100 includes a scanner portion 108, a printer portion 109, and an ink tank 110. In the printer 100, a print function is realized by the printer portion 109, and a scanning function is realized by the scanner portion 108. The printer portion 109 prints an image on a recording medium such as a print sheet by an inkjet scheme on the basis of image data received from the outside, image data read from the scanner portion 108, and the like. The printer portion 109 includes an inkjet head, and ink which is a consumable material is supplied from the ink tank 110 to the inkjet head via a tube. Also, the printer portion 109 manages ink information and sheet information. The ink information is information regarding ink used by the printer 100 and includes information regarding the remaining amount of ink in the ink tank 110. The sheet information is information regarding sheets used by the printer 100 and includes information regarding the number of mounted sheets and information regarding the number of printed sheets. The scanner portion 108 optically reads an original document set in an original document table 201, converts the original document into electronic data, and transmits it to an external device via a network, or copies it. The aforementioned parts are respectively connected to each other with the system bus 111 and can transmit and receive data to and from each other. The ink tank 110 stores ink therein. The ink is refilled from an ink bottle into the ink tank 110.

FIG. 2 is a diagram illustrating an appearance of the printer 100. The printer 100 includes the display portion 106, the operation portion 107, the ink tank 110, and the original document table 201. Also, a QR code 202 is applied (attached) to the printer 100. Note that although the ink tank 110 is seen from the outside and is configured such that the remaining amount of ink can be visually checked by the user in the example illustrated in FIG. 2, the ink tank 110 may be provided inside the printer 100 and may be disposed at a position at which the ink tank 110 is not seen from the outside.

The QR code 202 is a code image in which a printer serial ID for identifying the printer is coded. In the QR code 202, not only the printer serial ID but also a product name, an URL of a server that is a connection destination, activation information that is read by a mobile terminal to start a corresponding application, performance of the printer, and the like may be additionally coded. Also, a plurality of QR codes for each piece of the aforementioned information may be disposed on the printer 100. Note that although the case where the code image is a QR code will be described as an example in the present embodiment, the present disclosure is not limited thereto, and the code image may be a two-dimensional code such as a barcode, for example. Also, although the example in which the QR code 202 is attached to the surface of the printer 100 will be described in the present embodiment, a mode in which the QR code 202 is displayed on the display portion 106 may also be adopted.

FIGS. 3A and 3B are diagrams for explaining the ink tank 301 and the ink. FIG. 3A is a diagram for explaining a method of refilling the ink. If an ink tank cover 301 of the printer 100 is opened, then it is possible to access the ink tank 110. The printer 100 can eject a plurality of types of ink with different colors and record a color image on a recording medium. Therefore, the ink tank 110 is provided with four types of ink tanks to accommodate ink of four colors, namely yellow, cyan, magenta, and black. In the following description, letters C for cyan, M for magenta, Y for yellow, and Bk for black will be applied in order to simply denote the four colors. The ink tank 110 includes an ink tank 110C for accommodating cyan-colored ink, an ink tank 110M for accommodating magenta-colored ink, an ink tank 110Y for accommodating yellow-color ink, and an ink tank 110Bk for accommodating black-color ink. Each of the ink tank 110C, the ink tank 110M, the ink tank 110Y, and the ink tank 110Bk includes an ink inlet port 302. A cap at the inlet port 302 is opened, and the ink is supplied from an ink bottle 303 into the ink tank 110. The inlet port 302 of the ink has a different shape for each color such that it is not possible to refill ink from the ink bottle of a different color in this mechanism. Also, the inlet ports 302 may also be produced with differences in shape not only for each color but also for inks of different compositions which change in color when mixed to guarantee image quality. Note that although the example in which four types of ink tanks are provided will be described in the present embodiment, the number of ink tanks may be one or more.

FIG. 3B is a diagram for explaining an ink bottle. The ink bottle 303 is a container of ink which is a consumable material. The ink bottle 303 includes an ink bottle 303C in which the cyan-colored ink is placed, an ink bottle 303 in which the magenta-color ink is placed, an ink bottle 303Y in which the yellow-color ink is placed, and the ink bottle 303Bk in which the black-color ink is placed. When the ink tank 110C for accommodating the cyan-color ink is filled with ink, ink is supplied from the ink bottle 303C in which the cyan-color ink is placed.

FIG. 4 is a diagram illustrating a configuration of a system according to a first embodiment. The system is a system that requests delivery of the ink bottle 303 from a delivery service in accordance with the remaining amount of ink or the amount of used ink and realizes automatic delivery of the ink bottle 303 and includes a plurality of printers 100, a mobile terminal 402, and a server 401. The printers 100 are recording devices of an ink bottle scheme of refilling ink by using the ink bottles 303. The plurality of printers 100 (for example, a printer 100a and a printer 100b) in the system share the ink bottle 303 that is a container of a consumable material. Therefore, ink is supplied from the ink bottle 303 to both the printer 100a and the printer 100b. Information regarding the ink consumed by each printer 100 is sent from each printer 100 to the mobile terminal 402.

The mobile terminal 402 is a network device that has a communication function such as a smartphone or a tablet terminal, for example. Communication between the printers 100 and the mobile terminal 402 may be configured of, for example, any one of a wireless LAN, Bluetooth, a cellular network (for example, LTE or 5G), the Internet line, infrared communication, and wired communication, or a combination thereof. Also, the mobile terminal 402 includes a camera portion that is an imaging section that captures an image. The server 401 is an information processing device that provides an ink bottle automatic delivery service, that is, a delivery service of delivering the container of the consumable material that is used by the devices. A new ink bottle is automatically delivered to the user who is subscribed to the ink bottle automatic delivery service when the amount of consumed ink exceeds a specific threshold value. Communication between the mobile terminal 402 and the server 401 may be configured of any one of a communication network such as a LAN or a WAN, a cellular network, a wireless network, a telephone line, and a dedicated digital line, or a combination thereof. In other words, it is only necessary for data to be able to be transmitted and received according to the configuration, and any scheme can be employed as a communication scheme. Also, the delivery service may be realized not only by the server 401 but also by a virtual machine (cloud service) using resources provided by a data center including one or more information processing devices in addition to the information processing devices or a combination thereof.

FIG. 5 is a diagram for explaining a mechanism of ink supply. Note that although a configuration of only one color will be described here for easy understanding, the present disclosure is not limited to the configuration of only one color. A recording head 501 is a recording head of an inkjet scheme and ejects ink onto a recording medium such as a sheet. The recording head 501 is mounted on a carriage 502. A guide shaft 503 is a guide to support the carriage 502. A carriage motor 504 is a motor that drives the carriage 502. A belt 505 is a transmission mechanism of transmitting a drive force of the carriage motor 504 to the carriage 502. The belt 505 is rotated by the carriage motor 504 being driven, the carriage 502 coupled to the belt 505 is caused to move leftward and rightward in FIG. 5 along the guide shaft 503, and the recording head 501 is caused to move to a recording position. The driving of the carriage motor 504, that is, the position of the recording head 501 is controlled by the CPU 101.

The ink tank 110 stores ink 508. Also, a supply tube 511 is attached to the ink tank 110. The supply tube 511 is a tube for supplying the ink from the ink tank 110 to the recording head 501. The ink 508 is supplied from the ink tank 110 to the recording head 501 via the supply tube 511 and is then

ejected. A choke valve 512 is provided in the middle of the supply tube 511. The choke valve 512 blocks or opens a flow path between the ink tank 110 and the recording head 501. Specifically, the ink is temporarily dammed by closing the choke valve 512 provided in the middle of the supply tube 511, the pressure on the side of the recording head 501 from the choke valve 512 in the supply tube 511 is reduced such that the pressure in the internal space therein becomes a negative pressure. Then, the choke valve 512 is opened in this state, and the ink is supplied to the recording head 501.

Also, a pair of an electrode 509 and an electrode 510 are provided in the ink tank 110 in a state where the electrodes can come into contact with the ink 508. The CPU 101 obtains a voltage or the like that is a potential difference at the time of an application of a voltage to the electrode 509 and the electrode 510 and at the time of ending the application, compares the electrical information with a threshold value that is a reference value, and thereby measures the remaining amount of ink in the ink tank 110. Additionally, the CPU 101 can also calculate the amount of consumed ink from a difference between the remaining amount of ink when the count of the amount of consumed ink is initialized and the current remaining amount of ink. Note that the method of measuring the remaining amount and the amount of consumed ink performed by the CPU 101 is not limited thereto. For example, the amount of used ink and the remaining amount may be estimated on the basis of print data.

The cap unit 506 is a cap that comes into close contact with an ejection surface of the recording head 501 to prevent the ejection surface of the recording head 501 from being dried and being not able to eject ink. Also, the cap unit 506 also has a function as a recovery section that performs recovery operations such as empty ejection and suctioning recovery on the nozzle array of the recording head 501. A discharge tube 513 is a tube for discharging the ink to a discarded ink absorber 514. A suctioning pump 515 is a pump that suctions the ink in the recording head 501 and the supply tube 511 and discharges the ink to the discarded ink absorber 514. Specifically, the suctioning pump 515 causes the ejection surface of the recording head 501 to come into close contact with the cap unit 506, reduces the pressure in the cap unit 506, and thereby suctions the ink in the recording head 501 and the supply tube 511. The suctioning pump 515 can thus perform supply of the ink to the recording head 501 and the suctioning recovery operations of discharging air bubbles inside the recording head 501 and the supply tube 511 along with the ink. The discarded ink absorber 514 stores the ink passing, suctioned, and discharged through the discharge tube 513.

FIG. 6 is a diagram illustrating an appearance of an ink bottle. Here, the ink bottle 303 will be described by exemplifying an ink bottle 303C. An outlet port 601 is an outlet port of ink 604 and has a structure in which refilling of the ink 604 is started when the distal end thereof is combined with the inlet port 302. The shape of the outlet port 601 differs for each color to prevent the ink of an incorrect color from being refilled. Also, the outlet port 601 is produced with a change in shape not only for each color but also to guarantee image quality for ink which exhibits a different tone when it is mixed due to a different composition of the ink.

A small window 602 is a small window for the user to visually check the remaining amount of the ink 604. The small window 602 is made of a transparent member, and the small window 602 is provided with a scale 603. On the other hand, a material of the ink bottle 303C other than the small

window **602** is a material that does not completely transmit light in order to reduce an optical change in ink **604**. The user can recognize the remaining amount of ink **604** in the ink bottle **303C** by reading the scale **603** of the small window **602** and the surface of the ink **604** together. Note that although the mechanism of recognizing the remaining amount through the small window **602** has been described, the entire bottle may be transparent in a case of an ink of a material that is unlikely to be optically changed.

Also, a QR code **605** is applied to the surface of the ink bottle **303C**. The QR code **605** is a code image in which information necessary to manage the ink bottle is incorporated. The information necessary to manage the ink bottle includes at least a serial ID of the ink bottle for uniquely identifying the ink bottle. Also, the information necessary to manage the ink bottle may include information related to the ink bottle such as an ink model, an ink color, the initial remaining amount, and a manufacturing date, connection information (URL) to a server that manages the ink bottle, an activation information of the application that manages the ink bottle, and the like. Note that although the case where the code image is a QR code will be described as an example in the present embodiment, the present disclosure is not limited thereto, and the code image may be a two-dimensional code such as a barcode, for example.

FIG. 7 is a diagram for explaining an ink bottle record managed by each printer **100**. An ink bottle record **701** is history information of ink bottles used by the printer **100** and is managed by the EEPROM **104** of the printer **100** and the server **401**. The ink bottle record **701** holds an ink bottle record for each ink bottle (an ink bottle record **702**, an ink bottle record **707**, and an ink bottle record **708**) in the form of a list.

The ink bottle record **702** will be described as an example of the ink bottle record for each ink bottle. The ink bottle record **702** includes a serial ID **703** of the ink bottle, bottle information **704**, server management information **705**, and service information **706**. The serial ID **703** of the ink bottle is information for uniquely identifying the ink bottle. The bottle information **704** stores information such as an ink color, ink capacity, a manufacturing date of the ink, and the like. The server management information **705** stores connection information to the server **401**, security information for establishing connection, and information such as a flag indicating whether registration in the server has been made. The service information **706** stores information such as a subscription condition of the ink bottle automatic delivery service and a previous delivery date, for example.

FIG. 8 is a diagram illustrating a hardware configuration of the mobile terminal **402**. The mobile terminal **402** includes a main board **801** that performs main control of the mobile terminal **402** and a communication portion **817** that performs communication with the outside. The main board **801** includes a CPU **802**, a ROM **803**, and a RAM **804**. The communication portion **817** is a unit for performing data communication with the outside, such as a WLAN unit that performs WLAN communication, for example. The communication portion **817** is connected to a system bus **818** of the main board **801** via a bus cable **816**.

The CPU **802** controls the entire mobile terminal **402**. The ROM **803** stores a control program, an incorporated operating system (OS) program, and the like executed by the CPU **802**. Each control program stored in the ROM **803** performs basic software control such as scheduling, task switching, and the like under management of the incorporated OS stored in the ROM **803**. The RAM **804** is configured of a static RAM (SRAM) or the like, stores program

control variables and the like, and stores setting values registered by the user, management data of the mobile terminal **402**, and the like. Additionally, the RAM **804** is provided with buffer regions for various works. The CPU **802** comprehensively controls each part connected to a system bus **818** and controls the entire mobile terminal **402** by executing the programs stored in the ROM **803**.

The main board **801** further includes an image memory **805**, a data accumulation portion **812**, a non-volatile memory **815**, a data conversion portion **806**, a telephone portion **807**, an operation portion **808**, a GPS **809**, and a display portion **810**. The image memory **805** includes a dynamic RAM (DRAM) or the like and temporarily stores image data received via the communication portion **817** and image data read from the data accumulation portion **812** in order to process them by the CPU **802**. The non-volatile memory **815** includes a flash memory and the like and stores data that it is desired to store even after the power source of the mobile terminal **402** is turned off. For example, information regarding the printer **100** read by the application and the like are stored in the non-volatile memory **815**. The data accumulation portion **812** stores image data captured by a camera portion **811**. Note that the memory configuration of the mobile terminal **402** is not limited to the configuration described above. For example, the image memory **805** and the RAM **804** may be shared, or data backup in the data accumulation portion **812** or the like may be performed. Also, although the example in which the DRAM is used as the image memory **805** has been described in the present embodiment, a non-volatile memory, an attachable/detachable hard disk, or the like may be used.

The data conversion portion **806** performs analysis of a page description language (PDL) and the like and data conversion such as color conversion and image conversion. The telephone portion **807** controls a telephone line and realizes communication through a telephone by processing audio data input and output via a speaker portion **813**. The operation portion **808** receives input operations from the user. The display portion **810** is a liquid crystal display or an organic EL display, for example, and displays various input operations and operation conditions, status conditions, and the like of the mobile terminal **402**. Note that the operation portion **808** and the display portion **810** may be integrated like a touch panel. It is possible to configure a GUI that allows the user to perform operations as if the user were able to operate directly the screen displayed on the touch panel by associating input coordinates with display coordinates on the touch panel. A global positioning system (GPS) **809** acquires current position information such as a latitude and a longitude.

The main board **801** further includes the camera portion **811**, the speaker portion **813**, and a power source portion **814**. The camera portion **811** includes an imaging optical system and an imaging sensor, uses the imaging sensor to perform photoelectric conversion of light that is incident via the imaging optical system, and acquires an image. The image captured by the camera portion **811** is saved in the data accumulation portion **812**. Also, it is possible to acquire the information stored in the code image by the camera portion **811** reading the code image such as a QR code. The speaker portion **813** inputs and outputs sound. For example, the speaker portion **813** inputs or outputs audio for a telephone function or outputs sound on the basis of an alarm notification. The power source portion **814** controls a power source and a battery of the mobile terminal **402**. Each component of the main board **801** and the communication

portion **817** are connected to each other via the system bus **818** managed by the CPU **802**.

FIG. 9 is a diagram illustrating a software configuration of the mobile terminal **402**. The mobile terminal **402** includes a registration APP **901**, a delivery APP **910**, an imaging section **920**, and a communication section **921**. Each section illustrated in FIG. 9 is realized by the CPU **802** reading and executing, in the RAM **804**, the control program stored in the memory such as the ROM **803**. Note that although the example in which two applications, namely the registration APP **901** and the delivery APP **910** are registered in the mobile terminal **402** will be described in the present embodiment, the registration APP **901** and the delivery APP **910** may be realized as one application. The imaging section **920** controls the camera portion **811** and captures and acquires an image. The communication section **921** controls communication with external devices (for example, the printers **100**, the server **401**, and the like) via the communication portion **817**.

The registration APP **901** is an application for registering printer information and ink bottle information. In the mobile terminal **402** and the server **401**, the printer information is managed as a printer record (FIG. 10), and the ink bottle information is managed as an ink bottle record (FIG. 11). The registration APP **901** includes a printer management section **902**, an ink bottle management section **903**, and a display control section **904**. The printer management section **902** of the registration APP **901** acquires information regarding the printers **100** and registers and manages the information as a printer record. The processing of registering the information regarding the printers **100** will be described later by using FIG. 12. The ink bottle management section **903** of the registration APP **901** acquires the information regarding the ink bottle **303** and registers and manages the information as an ink bottle record. The processing of registering the information regarding the ink bottle **303** will be described later by using FIG. 14. The display control section **904** of the registration APP **901** controls display on the display portion **810** of the screen provided by the registration APP **901**.

The delivery APP **910** is an application that provides a request for delivery to the delivery service of the ink bottle on the basis of the total amount of consumption obtained by summing the amounts of consumed ink or the remaining amounts of the ink. The delivery APP **910** includes an ink bottle management section **911**, an acquisition section **912**, a delivery request section **913**, and a display control section **914**. The ink bottle management section **911** manages the ink bottle record registered by the registration APP **901**. The acquisition section **912** acquires information including the amounts of consumed ink or the remaining amounts from the printers. The delivery request section **913** determines whether or not it is necessary to provide a request to deliver the ink bottle and provides the request for delivery to the delivery service on the basis of the information acquired by the acquisition section **912**. The display control section **914** controls display on the display portion **810** of the screen provided by the delivery APP **910**. The processing executed by the delivery APP **910** will be described later by using FIGS. 15 and 16.

FIG. 10 is a diagram for explaining a printer record. A printer record **1001** is a list of printer information managed by the mobile terminal **402** and is stored in the non-volatile memory **815**. The printer record **1001** stores a printer record for each printer (a printer record **1002**, a printer record **1013**, and a printer record **1014**) in the form of a list.

The printer record **1002** will be described as an example of the printer record for each printer. The printer record **1002** includes manufacturing information **1003** and field information **1008**. The manufacturing information **1003** is information determined when the printer is manufactured. The manufacturing information **1003** includes a serial ID **1004** of the printer, a manufacturing date **1005**, a product name **1006**, and ink information **1007**. The serial ID **1004** of the printer is information for uniquely identifying the printer and is numbered at the time of manufacturing. The manufacturing date **1005** is a date and time when the printer is manufactured. The product name **1006** is a product name of the printer. The ink information **1007** stores information regarding ink used by the printer.

The field information **1008** is information changed after the printer is used at the user destination. The field information **1008** includes a registration date **1009**, service information **1010**, and a used ink bottle ID **1011**. The registration date **1009** stores the registration date on which the printer is registered. The service information **1010** stores a subscription condition of a service supporting the printer and a log indicating execution of the service. For example, the service information **1010** stores information such as a subscription condition of the ink bottle automatic delivery service and a previous delivery date. The service information **1010** stores information similar to the service information **706** in regard to the ink. Also, the service information **1010** may store unique information, and for example, a date and time when communication with the server is performed, information regarding a point service, and the like may be stored therein. The used ink bottle ID **1011** includes a serial ID that uniquely identifies the ink bottle used by the printer. The ID registered in the used ink bottle ID **1011** is information that is similar to the serial ID **703** of the ink bottle. In a case of a printer using a plurality of types of ink, a plurality of used ink bottle IDs are registered in accordance with the number of types of the ink like the used ink bottle ID **1012**.

FIG. 11 is a diagram for explaining an ink bottle record managed by the mobile terminal **402**. The ink bottle record is a list of ink bottle information managed by the mobile terminal **402** and is stored in the non-volatile memory **815**. The ink bottle record **1101** stores an ink bottle record for each ink bottle (an ink bottle record **1102**, an ink bottle record **1114**, and an ink bottle record **1115**) in the form of a list.

The ink bottle record **1102** will be described as an example of the ink bottle record for each ink bottle. The ink bottle record **1102** includes manufacturing information **1102** and field information **1108**. The manufacturing information **1103** is information determined when the ink bottle is manufactured. The manufacturing information **1103** includes a serial ID **1104** of the ink bottle, a manufacturing date **1105**, an ink size **1106**, and an ink color **1107**. The serial ID **1104** of the ink bottle is information for uniquely identifying the ink bottle and is numbered at the time of manufacturing. The manufacturing date **1105** is a date and time when the ink bottle **303** is manufactured. The ink size **1106** is information indicating the capacity of the ink bottle. The ink size **1106** may store actual capacity such as 100 ml, 200 ml, or 300 ml, for example, or may store the size of relative capacity such as large, middle, and small. The ink color **1107** is a color of the ink in the ink bottle and stores information indicating a specific color such as cyan, magenta, or yellow, for example.

The field information **1108** is information changed after the ink bottle is used at a user destination. The field

information 1108 stores a used printer ID 1109, a registration date 1111, delivery information 1112, and service information 1113. The used printer ID 1109 stores a serial ID of the printer using the ink bottle. In a case where one ink bottle is used by a plurality of printers, serial IDs of the plurality of printers using the ink bottle are registered. In the example of the ink bottle record 1102, two used printer IDs, namely the used printer ID 1109 and the used printer ID 1110 are registered. The registration date 1111 stores a registration date on which the ink bottle is registered. The delivery information 1112 stores delivery information of the ink bottle. An initial state of the delivery information 1112 is “not yet delivered” and is updated when the request to deliver the ink bottle is provided. The timing at which the delivery information 1112 is updated will be described in FIG. 15. The service information 1113 includes information such as connection information (URL) to the ink bottle automatic delivery service, a service subscription condition, and a previous delivery time. The service information 1010 stores information that is similar to the service information 706 in regard to the ink. Also, the service information 1010 may store unique information, and for example, a date and time when communication with the server is performed, information regarding a point service, and the like may be stored therein. Note that the ink bottle record stored in the server 401 also has a structure that is similar to that of the ink bottle record held by the mobile terminal 402 described in FIG. 11.

FIG. 12 is a sequence diagram illustrating processing of registering the printer 100 in the server 401. In the present embodiment, the serial ID of the printer 100 that has not yet been registered is acquired by using the mobile terminal 402 and is registered in the server 401. The processing performed by the mobile terminal 402 illustrated in FIG. 12 is realized by the CPU 802 of the mobile terminal 402 reading and executing, in the RAM 804, the control program stored in a memory such as the ROM 803. FIGS. 13A to 13D are diagrams illustrating examples of display of the mobile terminal 402.

S1201, the mobile terminal 402 activates the registration APP 901 on the basis of a user's instruction. In S1202, the registration APP 901 displays a screen for encouraging the user to image the QR code on the printer to be registered. The user images the QR code 202 on the printer 100 by the camera portion 811 of the mobile terminal 402 in accordance with an instruction from the registration APP 901. FIG. 13A is a diagram illustrating an example of display on the screen of the mobile terminal 402 when the QR code 202 on the printer 100 is imaged. The image of the QR code 202 for identifying the printer 100 capturing the image through the camera portion 811 and a guidance 1301 for providing an instruction for an imaging operation to the user are displayed on the display portion 810. In a case where the image of the QR code 202 is missed, or an imaging angle is not appropriate for reading the QR code 202, for example, an instruction to correct the imaging state is displayed as the guidance 1301 for the user.

In S1203, the printer management section 902 of the registration APP 901 analyzes the captured image of the QR code 202 and acquires information regarding the printer including the serial ID of the printer 100. For example, the registration APP 901 may acquire the manufacturing information such as a product name, a manufacturing date, and ink information of the printer 100, the field information, and the like from the QR code 202 in addition to the serial ID of the printer 100. Furthermore, the registration APP 901 may acquire connection information of the server 401 from the

QR code 202. Then, the registration APP 901 registers the acquired information in the printer record and stores the printer record in the non-volatile memory 815. FIG. 13B is a diagram illustrating an example of a screen that displays a result of analyzing the QR code 202. Image analysis information 1302 is displayed on the display portion 810. A result of analyzing the QR code 202 is displayed in the image analysis information 1302. A serial ID, a product name, a connection destination server ID, and the like of the printer, for example, are displayed in the image analysis information 1302. Also, in a case where the printer from which the QR code 202 is read has not yet been registered, a registration button 1303 may be displayed. The registration button 1303 is a button for registering the printer displayed in the image analysis information 1302 in the printer record 1001.

In S1204, the printer management section 902 of the registration APP 901 sends the printer record generated in S1203 as information regarding the printer 100 to be registered to the server 401. In S1205, the server 401 registers the printer record acquired from the mobile terminal 402. In S1206, the server 401 notifies the mobile terminal 402 of completion of registration of the printer information, and the registration APP 901 that has received the notification ends this flow. Through the above processing, it is possible to register the printer 100 that has not yet been registered in the server 401 as a target of the service provided by the server 401.

FIG. 14 is a sequence diagram illustrating processing of registering the ink bottle 303. In the present embodiment, the serial ID of the ink bottle 303 that has not yet been registered is acquired and registered in the server 401 and the printer 100 by using the mobile terminal 402. The processing performed by the mobile terminal 402 illustrated in FIG. 14 is realized by the CPU 802 of the mobile terminal 402 reading and executing, in the RAM 804, the control program stored in a memory such as the ROM 803.

In S1401, the mobile terminal 402 activates the registration APP 901 on the basis of a user's instruction. In S1402, the registration APP 901 displays a screen for encouraging the user to image the QR code on the ink bottle to be registered. The user images the QR code 605 on the ink bottle 303 by using the camera portion 811 of the mobile terminal 402 in accordance with an instruction from the registration APP 901. FIG. 13C is a diagram illustrating an example of display on the screen when the QR code 605 on the ink bottle 303 is imaged. The image of the QR code 605 for identifying the ink bottle 303 imaged through the camera portion 811 and a guidance 1310 for providing an instruction for an imaging operation to the user are displayed on the display portion 810. In a case where the image of the QR code 605 is missed, or an imaging angle is not appropriate to read the QR code 202, an instruction to correct the imaging state is displayed as the guidance 1310 for the user.

In Step S1203, the ink bottle management section 903 of the registration APP 901 analyzes the captured image of the QR code 605 and acquires information regarding the ink bottle including the serial ID of the ink bottle 303. For example, the registration APP 901 may acquire the manufacturing information such as a manufacturing date, capacity, and a color of the ink bottle 303, the field information, and the like from the QR code 605 in addition to the serial ID of the ink bottle 303. Also, the registration APP 901 may acquire connection information of the server 401 from the QR code 605. Then, the ink bottle management section 903 of the registration APP 901 registers the acquired information in the ink bottle record and stores the information in the non-volatile memory 815. FIG. 13D is a diagram illustrating

an example of a screen that displays a result of analyzing the QR code **605**. Image analysis information **1311** and printer information are displayed on the display portion **810**. A result of analyzing the QR code **605** is displayed in the image analysis information **1311**. The ink bottle ID, the ink capacity, the ink color, and the like are displayed in the image analysis information **1311**, for example. Additionally, the printer **100** registering the ink bottle ID corresponding to the image analysis information **1311** is displayed in the printer information **1312**. In addition, the printer **100** using the ink bottle corresponding to the image analysis information **1311** may be able to be registered in the printer information **1312**. Also, in a case where the ink bottle **303** with the QR code **605** applied thereto has not yet been registered, a registration button **1313** may be displayed. The registration button **1313** is a button for registering the ink bottle displayed on the image analysis information **1311** in the ink bottle record **1101**.

In **S1404**, the ink bottle management section **903** of the registration APP **901** sends the ink bottle record generated in **S1203** to the server **401** as information regarding the ink bottle **303** to be registered. In **S1405**, the server **401** updates the ink bottle record managed by the server **401** on the basis of the ink bottle record sent from the mobile terminal **402**. In **S1406**, the server **401** notifies the mobile terminal **402** of completion of registration of the ink bottle information.

In **S1407**, the mobile terminal **402** sends the ink bottle record generated in **S1203** as information regarding the ink bottle **303** to be registered to the printer **100** using the ink bottle **303**. In **S1408**, the printer **100** updates the ink bottle record managed by the printer **100** on the basis of the ink bottle record sent from the mobile terminal **402** and completes the processing. Through the above processing, it is possible to register the information regarding the ink bottle including the serial ID of the ink bottle in the server **401** and to further reflect the information in the printer **100** as well by imaging the ink bottle by the mobile terminal **402**.

FIGS. **15** and **16** are sequence diagrams illustrating processing of determining a request (order) to deliver ink by using the mobile terminal **402**. FIG. **15** illustrates an example in which whether or not it is possible to provide a request for delivery is determined on the basis of a total value of the amounts of consumed ink (the total amount of consumed ink), and FIG. **16** illustrates an example in which whether or not it is possible to provide a request for delivery is determined on the basis of the remaining amount of ink. The processing performed by the mobile terminal **402** illustrated in FIGS. **15** and **16** is realized by the CPU **802** of the mobile terminal **402** reading and executing, in the RAM **804**, the control program stored in a memory such as the ROM **803**.

First, the case where whether or not it is possible to provide a request for delivery is determined on the basis of the total value of the amounts of consumed ink will be described by using FIG. **15**. The processing of providing a request to deliver the ink is executed for each ink bottle record held by the mobile terminal **402**. Here, the ink bottle record **1102** illustrated in FIG. **11** will be described as an example. In **S1501**, the mobile terminal **402** activates the delivery APP **910** of the ink bottle on the basis of a user's instruction. Note that the mobile terminal **402** can also automatically activate the delivery APP at a timing set in advance by the user.

In **S1502**, the acquisition section **912** of the delivery APP **910** acquires the amount of consumed ink from all the printers, the used printer IDs of which are registered in the field information **1108** of the ink bottle record **1102**. In a case

where whether or not to provide a request to deliver the ink bottle **303** corresponding to the ink bottle record **1102** is determined, the mobile terminal **402** acquires the amount of consumed ink from the printers corresponding to the used printer ID **1109** and the used printer ID **1110**. Here, the amount of consumed ink acquired from each printer is the amount of ink consumed after the previous amount of consumed ink is initialized (S1511). Any method can be used to acquire the amount of consumed ink from the printer, for example, by a method of acquiring it via a printer management application that monitors an operating condition of the printer including the amount of consumed ink.

In **S1503**, the delivery request section **913** of the delivery APP **910** calculates the total value of the amounts of consumed ink acquired from the printers and compares the calculated total value of the amounts of consumed ink with a threshold value. In a case where the total value of the amounts of consumed ink is less than the threshold value, it is not necessary to deliver the next ink bottle so far, and the processing is thus ended. On the other hand, in a case where the total value of the amounts of consumed ink is equal to or greater than the threshold value, the processing in **S1504** is performed to ask for delivery of the next ink bottle.

In **S1504**, the delivery request section **913** of the delivery APP **910** checks delivery information **1112** of the ink bottle record. In a case where the value of the delivery information **1112** is a value indicating that processing for delivery has been performed, such as "already delivered", the processing is ended. On the other hand, in a case where the value of the delivery information **1112** is "not yet delivered", the processing in **S1505** is performed. In **S1505**, the delivery request section **913** of the delivery APP **910** transmits the ink bottle ID and the request to deliver the ink bottle to the server **401**. In **S1506**, the server **401** receives delivery of the ink bottle from the mobile terminal **402**. In **S1507**, the server **401** updates the ink bottle record managed by the server **401**. In **S1508**, the server **401** notifies the mobile terminal **402** of completion of reception of the delivery of the ink bottle. In the mobile terminal **402** that has received the notification of completion of reception of the delivery from the server **401**, the ink bottle management section **903** of the delivery APP **910** updates the delivery information **1112** of the ink bottle record **1102** to "already delivered" in **S1509**. In **S1510**, the delivery APP **910** provides an instruction to initialize the amounts of consumed ink to the printers corresponding to the used printer IDs (the used printer ID **1109** and the used printer ID **1110**) registered in the ink bottle record **1102**. The printers that have received the instruction to initialize the amounts of consumed ink initialize the amounts of consumed ink in **S1511**.

Note that although the example in which the mobile terminal **402** automatically provides a request for delivery in the case where the value of the delivery information **1112** is "not yet delivered" in **S1504** has been described in the present embodiment, the user may be able to select whether or not it is necessary to provide the delivery. For example, the mobile terminal **402** notifies a user of a screen for checking whether to provide a request for delivery along with the total value of the amounts of consumed ink calculated in **S1503** and provides the request for delivery in **S1505** only in a case where the user selects the delivery.

Next, a case where whether or not it is possible to provide a request for delivery on the basis of the remaining amount of ink will be described by using FIG. **16**. The processing of providing a request to deliver the ink is executed for each ink bottle record held by the mobile terminal **402**. Here, the ink bottle record **1102** illustrated in FIG. **11** will be described as

15

an example. Note that the same reference signs will be applied to processing that is similar to that in FIG. 15, and description thereof will be omitted.

In S1601, the mobile terminal 402 acquires the remaining amounts of ink from all the printers, the used printer IDs have been registered in the field information 1108 of the ink bottle record 1102. In a case where whether or not to provide a request to deliver the ink bottle 303 corresponding to the ink bottle record 1102 is determined, the mobile terminal 402 acquires the remaining amounts of ink from the printers corresponding to the used printer ID 1109 and the used printer ID 1110. Any method can be used to acquire the amounts of consumed ink from the printers, for example, by a method of acquiring them via a printer management application that monitors an operating condition of the printers including the remaining amounts of ink.

In S1602, the mobile terminal 402 compares the remaining amount of ink acquired from each printer with a threshold value. In a case where there is even one remaining amount of ink that is less than the threshold value from among the remaining amounts of ink acquired from the printers, the processing in S1504 is performed. On the other hand, in a case where all the remaining amounts of ink acquired from the printers are equal to or greater than the threshold value, it is not necessary to deliver the next ink bottle so far, and the processing is thus ended.

In a case where there is a printer with a remaining amount of ink below the threshold value, the processing in S1504 to S1509 is performed similarly to FIG. 15, the delivery condition of the ink bottle is checked, a request for delivery is transmitted to the server 401 in a case where the ink bottle has not yet been delivered, and the ink bottle record is updated. As described above, the processing of providing a request for delivery on the basis of the remaining amount illustrated in FIG. 16 is ended. Note that whether or not to provide a request to deliver the ink bottle may be determined by combining determination based on the total of the amounts of consumed ink with determination based on the remaining amount of ink of each printer. For example, even if the total of the amounts of consumed ink does not reach the threshold value (first threshold value), the request to deliver the ink bottle is provided in a case where the remaining amount of the ink is less than the threshold value (second threshold value) in any of the printers. The initialization (S1511) of the amounts of consumed ink in the case where the total of the amounts of consumed ink is less than the threshold value and the request to deliver the ink bottle is provided is performed when the total of the amounts of consumed ink becomes equal to or greater than the threshold value rather than at the timing when the delivery information 1112 of the ink bottle becomes "already delivered". In this manner, it is possible to place an order for the ink bottle for filling the ink and to deliver it before the printer in which the ink is consumed early runs out of the ink even in a case where there is a large difference in amounts of consumed ink from among the plurality of printers.

FIGS. 17A and 17B are diagrams illustrating examples of a screen of displaying a result of determining delivery of the ink bottle. FIG. 17A is an example of display in a case where the total value of the amounts of consumed ink is less than the threshold value. The screen illustrated in FIG. 17A is displayed on the display portion 810 of the mobile terminal 402 after the processing in S1504 in FIG. 15. The ink bottle information 1701 is information regarding the ink bottle 303 that is a target of determination of delivery. The ink bottle information 1701 is displayed on the basis of the ink bottle record 1102. The ink bottle information 1701 includes, for

16

example, a serial ID, ink capacity, an ink color, and delivery information of the ink bottle. The printer information 1702 is information regarding the printer using the ink bottle displayed in the ink bottle information 1701. The printer information 1702 includes, for example, a printer ID for identifying the printer and the amount of consumed ink by the printer. Additionally, the printer information 1702 may include the remaining amount of ink in each printer. The delivery determination result 1703 is a result of performing determination regarding delivery of the ink bottle. The delivery determination result 1703 includes a total value 1704 of the amounts of consumed ink in the printers displayed in the printer information 1702 and a determination result 1705, for example. In a case where the total value of the amounts of consumed ink is equal to or greater than the threshold value, and an order to deliver a new bottle is placed, display to notify the user of the fact that the request for delivery has been provided is performed in the determination result 1705. On the other hand, in a case where the total value of the amounts of consumed ink is less than the threshold value, a guidance to notify the user of the threshold value to deliver the ink bottle is displayed.

FIG. 17B is an example of display in a case where the total value of the amounts of consumed ink is less than the threshold value (first threshold value) while there is a printer with the remaining amount of ink less than the threshold value (second threshold value). The screen illustrated in FIG. 17B is displayed on the display portion 810 of the mobile terminal 402 after the processing in S1504 in FIG. 16. The delivery determination result 1703 includes, for example, a total value 1704 of the amounts of consumed ink of the printers displayed in the printer information 1702 and a determination result 1706. A fact that there is a printer with the remaining amount of ink below the threshold value and a button for providing a request to deliver the ink bottle to the server 401 are displayed in the determination result 1706. The user can select the delivery of the ink bottle by operating the button displayed in the determination result 1706.

Although the example in which the ink bottle record is saved in both the non-volatile memory 815 of the mobile terminal 402 and the server 401 has been described in the present embodiment, the ink bottle record may be saved only in the server 401, and the ink bottle record may not be saved in the mobile terminal 402. The mobile terminal 402 that does not hold the ink bottle record acquires the information regarding the ink bottle from the server 401 as needed such as in a case where delivery of the ink is determined. In this manner, it is possible to determine the delivery even if the information regarding the ink bottle 303 is not stored in the non-volatile memory 815 of the mobile terminal 402, and it is possible to release the limited memory of the mobile terminal 402.

Also, although the example in which the code image is captured to acquire the information regarding the ink bottle has been described in the present embodiment, an IC chip provided to the printer or the ink bottle may be read by the mobile terminal 402 to acquire information regarding the printer or the ink bottle. Additionally, the imaging portion and the reading portion to acquire the information regarding the printer or the ink bottle may be devices externally provided to the network device. In addition, although the example of the ink used for printing by the printer has been described as a consumable material in the present embodiment, the present disclosure is not limited thereto, and the consumable material may be a material used for form shaping by a 3D printer that forms a three-dimensional

object by using the consumable material. It is possible to place an order for the material at an appropriate timing in a case where a material in the same container is used by a plurality of 3D printers.

As described above, according to the present embodiment, it is possible to estimate a timing at which consumption of ink is completed by summing the amounts of consumed ink at a plurality of printers even in a case where the ink is refilled to the printers from one ink bottle. Also, it is possible to estimate the timing at which the consumption of ink is completed in the printers even in a case where the amounts of consumed ink differ, by checking the remaining amount of ink in each printer. It is thus possible to place an order for the ink bottle at an appropriate timing even in a case where the one ink bottle is shared by the plurality of printers.

Second Embodiment

In the first embodiment, the example in which the program operating on the mobile terminal 402 calculates the total value of the amounts of consumed ink and determines whether or not to provide a request for delivery has been described. In the present embodiment, a mode in which the calculation of the total value of the amounts of consumed ink is performed by the server 401 that provides a delivery service of ink will be described. In other words, the server 401 realizes the functions of the delivery APP 910. Note that content of description that is common to the first embodiment will be omitted.

FIG. 18 is a diagram illustrating a configuration of a system according to the present embodiment. The system includes a server 401 that is a network device connected to a plurality of printers 100 via a network. Although the mobile terminal 402 manages the ink bottle information (ink bottle record) in the first embodiment, the ink bottle information is input to the printers 100 in the present embodiment. The printers 100 store the ink bottle information in the EEPROM 104. Also, the printers 100 transmit, to the server 401, information such as the ink bottle information, printer information, and the amounts of consumed ink input by users via the network. The server 401 calculates a total value of the amounts of consumed ink of the ink bottles on the basis of the information received from the printers. The server 401 that has calculated the total value of the amounts of consumed ink compares the total value of the amounts of consumed ink with a threshold value and performs determination regarding delivery of the ink bottle. Processing content of the determining of the delivery of the ink bottle based on the total value of the amounts of consumed ink is similar to the processing content in FIG. 15. Also, the server 401 may acquire the remaining amount of ink in each printer from the printer 100, compare the remaining amount of ink with a threshold value, and perform determination regarding delivery of the ink bottle similarly to the processing content in FIG. 16.

Also, although the server 401 acquires information such as the remaining amount of ink directly from the printers 100 and determines whether or not to provide a request for delivery in the present embodiment, the information from the printers 100 may be acquired via a network device such as the mobile terminal 402. The server 401 acquires information regarding the amounts of consumed ink, the remaining amounts, or the like from the printers 100 via the mobile terminal 402, calculates the total value of the amounts of consumption, compares the total value of the amounts of consumption with each threshold value, and determines

whether or not to deliver a new ink bottle. Additionally, the mobile terminal 402 may perform operations up to the calculation of the total value of the amounts of consumed ink and transmit the calculated total value to the server 401, and the server 401 may perform comparison with the threshold value. In addition, the device that collects information such as the amounts of consumed ink from the printers and transmits the information to the server 401 is not limited to the mobile terminal 402. Instead of the mobile terminal 402, 10 an information processing device such as a PC or a printer that functions as a monitoring device that monitors operating conditions of the plurality of printers may collect the information such as the amounts of consumed ink from the plurality of inks and transmit the information to the server 401.

As described above, according to the present embodiment, it is possible to place an order for an ink bottle at an appropriate timing even in a case where ink is refilled into a plurality of printers from one ink bottle.

OTHER EMBODIMENTS

Embodiment(s) of the present disclosure can also be realized by a computer of a system or apparatus that reads out and executes computer executable instructions (e.g., one or more programs) recorded on a storage medium (which may also be referred to more fully as a ‘non-transitory computer-readable storage medium’) to perform the functions of one or more of the above-described embodiment(s) and/or that includes one or more circuits (e.g., application specific integrated circuit (ASIC)) for performing the functions of one or more of the above-described embodiment(s), and by a method performed by the computer of the system or apparatus by, for example, reading out and executing the computer executable instructions from the storage medium to perform the functions of one or more of the above-described embodiment(s) and/or controlling the one or more circuits to perform the functions of one or more of the above-described embodiment(s). The computer may comprise one or more processors (e.g., central processing unit (CPU), micro processing unit (MPU)) and may include a network of separate computers or separate processors to read out and execute the computer executable instructions. The computer executable instructions may be provided to the computer, for example, from a network or the storage medium. The storage medium may include, for example, one or more of a hard disk, a random-access memory (RAM), a read only memory (ROM), a storage of distributed computing systems, an optical disk (such as a compact disc (CD), digital versatile disc (DVD), or Blu-ray Disc (BD)^{TM}), a flash memory device, a memory card, and the like.

While the present disclosure has been described with reference to exemplary embodiments, it is to be understood that the disclosure is not limited to the disclosed exemplary embodiments. The scope of the following claims is to be accorded the broadest interpretation so as to encompass all such modifications and equivalent structures and functions.

This application claims the benefit of Japanese Patent Application No. 2022-076540, filed on May 6, 2022, which is hereby incorporated by reference wherein in its entirety.

What is claimed is:

1. A system that manages at least one consumable material used by a plurality of devices, the system comprising:
a memory storing instructions; and
a processor executing the instructions causing the system to:

19

manage information regarding the consumable material for at least one container, acquire consumed amounts of the consumable material or remaining amounts of the consumable material from the plurality of devices using the consumable material in the respective container, and transmit information regarding a request to deliver a new container of the consumable material to a delivery service that delivers the new container of the consumable material used by at least one device among the plurality of devices on the basis of a total amount of consumption obtained by summing the consumed amounts of the consumable material of the plurality of devices or the remaining amounts of the consumable material of the plurality of devices.

2. The system according to claim 1, wherein the processor transmits the information regarding the request to deliver the new container of the consumable material to the delivery service in a case where the total amount of consumption obtained by summing the consumed amounts of the consumable material is equal to or greater than a threshold value, the total amount of consumption being acquired from the plurality of devices.

3. The system according to claim 1, wherein the processor transmits the information regarding the request to deliver the new container of the consumable material to the delivery service in a case where at least one remaining amount of the consumable material out of the remaining amounts of the consumable material acquired from the plurality of devices is less than a threshold value.

4. The system according to claim 1, wherein the information regarding the consumable material includes a delivery condition of the new container of the consumable material in the delivery service, and in a case where the delivery condition is a condition of not yet delivered, the processor transmits the information regarding the request to deliver the new container of the consumable material to the delivery service on the basis of a total amount of consumption obtained by summing the consumed amounts of the consumable materials or the remaining amounts of the consumable material.

5. The system according to claim 1, wherein the processor asks a user whether to ask for delivery of the new container in a case where it is determined that the request for the delivery is able to be provided on the basis of the total amount of consumption obtained by summing the consumed amounts of the consumable material or the remaining amounts of the consumable material, and the processor transmits the information regarding the request for the delivery to the delivery service in a case where the user asks for the delivery.

6. The system according to claim 1, wherein the information regarding the consumable material includes information uniquely identifying each of the plurality of containers of the consumable material and information uniquely identifying the plurality of devices that use the consumable material, and the processor acquires the consumed amounts of the consumable material and the remaining amounts of the consumable material from the plurality of devices corresponding to the information uniquely identifying the plurality of devices to which the consumable material has been refilled.

7. The system according to claim 1, wherein the processor acquires and registers the information regarding the consumable material by reading a two-dimensional code image attached to the container and further registers, in the infor-

20

mation regarding the consumable material, information indicating which of the plurality of devices uses the consumable material in the container.

8. The system according to claim 1, wherein counts of the consumed amounts of the consumable material transmitted to the system by the plurality of devices are initialized in a case where the total amount of consumption is equal to or greater than a threshold value.

9. The system according to claim 1, wherein the device is an image forming device that prints an image on a recording medium by using the consumable material or a 3D printer that forms a three-dimensional object by using the consumable material, and

the consumable material is ink used by the image forming device or a material used by the 3D printer.

10. The system according to claim 1, wherein a request to deliver the new container of the consumable material is provided by transmitting the information.

11. A network device comprising:
a memory storing instructions; and
a processor executing the instructions causing the network device to:

manage information regarding at least one consumable material for at least one container, acquire consumed amounts of the consumable material or remaining amounts of the consumable material from a plurality of devices using the consumable material in the respective container,

transmit information regarding a request to deliver a new container of the consumable material to a delivery service that delivers the new container of the consumable material used by at least one device among the plurality of devices on the basis of a total amount of consumption obtained by summing the consumed amounts of the consumable material or the remaining amounts of the consumable material, and capture an image.

12. A method of controlling a system that manages at least one consumable material used by a plurality of devices, the method comprising:

managing information regarding the consumable material for at least one container; acquiring consumed amounts of the consumable material or remaining amounts of the consumable material from the plurality of devices using the consumable material in the respective container; and

transmitting information regarding a request to deliver a new container of the consumable material to a delivery service that delivers the new container of the consumable material used by at least one device among the plurality of devices on the basis of the total amount of consumption obtained by summing the consumed amounts of the consumable material or the remaining amounts of the consumable material.

13. A non-transitory storage medium storing a control program of a system that manages at least one consumable material used by a plurality of devices, the control program causing a computer to perform each step of a control method of the system, the method comprising:

managing information regarding the consumable material for at least one container; acquiring consumed amounts of the consumable material or remaining amounts of the consumable material from the plurality of devices using the consumable material in the respective container; and

transmitting information regarding a request to deliver a new container of the consumable material to a delivery service that delivers the new container of the consumable material used by at least one device among the plurality of devices on the basis of the total amount of consumption obtained by summing the consumed amounts of the consumed consumable material or the remaining amounts of the consumable material. 5
